(57) **CLAIM**

The ornamental design for a pizza box, as shown and described.

DESCRIPTION

FIG. 1 is a perspective view of a pizza box showing our design;

FIG. 2 is a top view thereof;

FIG. 3 is a side elevational view thereof;

FIG. 4 is a side elevational view thereof, opposite that of FIG. 3;

FIG. 5 is a front elevational view thereof;

FIG. 6 is a rear elevational view thereof; and,

FIG. 7 is a bottom view thereof.

The circular broken line shown in FIGS. 1, 2, and 5 represents a perforation.
